DOOR

Bascom B. Westmoreland, Houston, Tex.

Application March 30, 1939, Serial No. 264,941

11 Claims. (Cl. 20—19)

This invention relates to a door.

The invention relates more particularly to a vertically movable, or what is commonly known as an overhead door and relates also to the means for mounting and operating the door.

The type of door and operating mechanism therefor has been particularly designed for use on garages and similar out buildings although it is capable of general use wherever a door of this type may be desired.

An object of the invention is to provide a door of the character described, which, when in closed position, stands vertically and which, when in open position, is disposed horizontally overhead.

Another object of the invention is to provide a novel mounting for the door whereby the door may be easily opened, that is, may be moved upwardly into horizontal, open position and safely maintained in that position and whereby the door may be readily moved into vertical, or closed position with safety and without danger of the door suddenly dropping and injuring itself or the operator.

A further object of the invention is to provide, in the door mounting, a tension member which is placed under tension as the door is lowered to closed position thus acting as a shock absorber and also preventing the sudden dropping of the door to closed position and which is maintained under sufficient tension to hold the door in open, or horizontal, position.

The invention also embodies racks on the door facing and on the door to which the door itself is geared and by means of which the door is guided into open or closed position.

With the above and other objects in view the invention has particular relation to certain novel features of construction, operation and arrangement of parts, an example of which is given in this specification and illustrated in the accompanying drawings, wherein—

Figure 1 shows an inside view of the door shown in closed position.

Figure 2 shows a horizontal, sectional view taken on the line 2—2 of Figure 1.

Figure 3 shows a vertical, sectional view taken on the line 3—3 of Figure 1, and

Figure 4 shows a sectional view of the door in open, horizontal, overhead position.

Referring now more particularly to the drawings wherein like numerals of reference designate the same parts in each of the figures, the numeral 1 designates the door which may be of any selected construction, which is preferably rectangular in shape to fit within and close the

opening 2 of a garage or other building structure 3.

Over the door opening there is a horizontal guide rod as 4 whose forward end is anchored to the building structure over the door opening and preferably centered with respect to said opening and whose other end is supported by any suitable anchor 5 usually a convenient portion of the building framework. Slidably mounted on the rod 4 there is a sleeve-like bearing 6 surrounding 10 which there is a clamp 7 open at one side and having the outwardly turned lugs 8, 8 in parallel relation. A link 9 has its upper end fitted between the lugs 8 and passing through said lugs and through said end of the link there is a clamp 15 bolt 10. The link is angle shaped having its ends arranged at approximately right angles to each other. Secured on the inner side of the door near the upper margin of the door are the brackets 11, 11 spaced apart between which the forward 20 end of the link is fitted and a clamp bolt 12 is fitted through said brackets and through the forward end of the link. The link is thus pivotally connected at one end to the door and at its other end to the clamp 7. Accordingly, as 25 the door is moved upwardly the bearing 6 will move inwardly along the guide rod or track 4 and the door will gradually move toward a horizontal position and when it reaches the limit of its upward movement it will assume a horizontal 30 position as shown in Figure 4.

At opposite margins of the door on the inner side thereof there are the rack members 13, 13 extending from the bottom of the door upwardly the required distance. The ends of said rack 35 members 13 are outwardly turned and secured to the door as more clearly shown in Figures 1 and 2 so as to space the racks themselves inwardly from the door. As shown these rack members 13 are formed of metal strips of the required 40 strength which have the spaced perforations 14 to receive the teeth of the corresponding gears 15, 15. These gears are located between the racks 13 and the door. They are fixed on the transverse drive shaft 16. Fastened to the door 45 on the inner sides of the racks 15 are the vertical angle irons 17, 17 whose outwardly extended flanges 18 form vertical tracks. Fixed on the shaft 16 are the grooved rollers 19 which run on said tracks 18 thus forming guide means for the 50 door.

On the inner side of the door facings are the vertical rack members 20, 20 whose ends are forwardly turned and fastened to the door facings. They extend from the top of the door 55

opening downwardly the required distance. They have the spaced perforations 21 to receive the teeth of the corresponding gears 22 which are also fixed on the shaft 16 and are located on the inner sides of said racks 20.

Fastened to the door facings, on the inner side thereof, and outwardly of the corresponding racks 20, are the channel shaped guides 23, 23 which are substantially coextensive, in length, with the corresponding racks 20. The flanges of the guides 23 are turned inwardly toward each other and rotatably mounted on the ends of the shaft 16 are the guide rollers 24, 24 which run in said channels 23 thus providing additional 15 guide means for the door.

Accordingly, as the door is elevated the racks 13 will turn the gears 15 and the shaft 16 and the gears 22 will be correspondingly turned and will travel up the racks 20. The gears 22 will be 20 maintained in mesh with the racks 20 by the guide rollers 24 and the guide channels 23.

Fastened on the shaft 16 between the tracks 18 there is a sleeve 25 which rotates with said shaft and loosely mounted on said sleeve there is 25 a tension arm 26. At one end this tension arm has an extended sleeve-like bearing 27 on the sleeve 25 and at its other end there is a grooved roller 28 mounted on said arm.

Fastened on the inside of the door 1 there is a 30 tension bracket 29. The ends of this bracket are forwardly turned and fastened to the door as more clearly shown in Figures 1, 2 and 3. It has an inwardly extended flange 30 extending from end to end thereof as more clearly shown in Figures 2 and 3 along which the roller 28 travels. On the sleeve 25 and fastened thereto there is a sleeve-like anchor 31 and surrounding this anchor at one end and surrounding the bearing 27 at its other end there is a coil tension spring 32 one 35 end of which is fastened to the anchor 31 and the other end of which is fastened to the tension arm 26. This spring is coiled in a direction such that as the door is lowered and the shaft 16 correspondingly turned the spring 32 will be 40 placed under tension thus causing the door to move gradually downwardly toward closed position, acting as a shock absorber and preventing the sudden dropping of the door. Accordingly, when the door is in closed position the spring 32 will be under considerable tension thus acting 45 as a counterbalance and acting to assist in elevating the door when it is desired to open the same. As the door is elevated the tension of the spring 32 will be only partially relieved to the 50 end that when the door is in fully opened position, as shown in Figure 4, the spring will still have sufficient tension to hold the door open. It is therefore evident that the spring 32, when installed, should be installed under considerable 55 tension sufficient to maintain the door open when in open position and as the door is closed the tension will be increased, for the purposes above stated, to not only permit the door to gradually move to closed position but to also assist in opening the door.

The drawings and description disclose what is now considered to be a preferred form of the invention by way of illustration only, while the broad principle of the invention will be defined 60 by the appended claims.

What I claim is:

1. In combination a building structure having an opening provided with side facings, a door for closing the opening, rack members on the facings, rack members on the door, a floating shaft 75

on the door geared to said rack members, guide means for guiding the door horizontally inwardly upon upward movement thereof, tension means arranged to be placed under tension by the shaft as the door is moved downward to closed position and to be relieved from said tension as the door is moved upwardly to open, horizontal position. 5

2. The combination with a structure having a door opening, of a door for closing the opening, a vertical rack on each side of the opening, a vertical rack on the door, a floating shaft on the door geared to said racks, and a tension member connected with the shaft and door and whose tension is varied as the door is moved upwardly 10 and downwardly.

3. The combination with a structure having an opening, of a vertical rack on the structure, a door for closing the opening, a rack on the door, a shaft on the door geared to the racks to rotate 20 in accordance with the door movements, a tension member connected to the shaft and door and whose tension varies in accordance with the rotation of the shaft.

4. The combination with a structure having an opening, of a vertical rack on the structure, a door movable upwardly into horizontal, open position and movable downwardly into vertical position to close the opening, a rack on the door, a shaft geared to said racks to rotate in accordance with the door movements, guide means for guiding the door into horizontal position upon upward movement of the door, a tension member operatively connected with the shaft and door and whose tension varies in accordance with the rotation of the shaft to check the movement of the door towards closed position. 25

5. The combination with a structure having an opening, of a vertical rack on the structure, a door movable upwardly into horizontal, open 40 position and movable downwardly into vertical position to close the opening, a rack on the door, a shaft geared to said racks to rotate in accordance with the door movements, guide means for guiding the door into horizontal position upon upward movement of the door, a tension member operatively connected with the shaft and door and whose tension varies in accordance with the rotation of the shaft to check the movement of the door towards closed position and to assist 45 the movement of the door toward open position.

6. The combination with a door of vertical, stationary racks, vertical, stationary guides, racks fixed on the door, a shaft, gear wheels fixed on the shaft in mesh with said racks, means on the shaft which cooperate with said guide to guide the movements of the shaft, a coil spring about the shaft one end of which is attached thereto, a tension arm on the shaft to which the other end of said spring is attached, means on the door 60 cooperating with the tension arm to maintain said spring under tension, said spring being arranged to be placed under tension upon movement of the door in one direction and to be relieved of tension upon movement of the door in 65 the other direction.

7. In combination vertical, stationary racks arranged on opposite sides of a door opening, a door movable into vertical position to close the opening and movable into a horizontal, overhead open position, racks on the door, a shaft geared to the stationary racks and to the racks on the door, stationary guides forming bearings along which the shaft moves as the door is moved to open or closed position. 70

8. In combination vertical, stationary racks arranged on opposite sides of the door opening, a door movable into vertical position to close the opening and movable into a horizontal, overhead open position, racks on the door, a shaft geared to the stationary racks and to the racks on the door, stationary guides forming bearings along which the shaft moves as the door is moved to open or closed position and guide means for guiding the door into horizontal position as the door is opened.
9. The combination with a structure having an opening, of a vertical rack on the structure, a door for closing the opening, a rack on the door, a shaft on the door geared to the racks to rotate in accordance with the door movements, a tension member connected to the shaft and door and whose tension varies in accordance with the rotation of the shaft, guides on the door and guide wheels on the shaft which travel along said guides as the door is moved.
10. In combination vertical, stationary racks arranged on opposite sides of the door opening, a door movable into vertical position to close the opening and movable into a horizontal, overhead open position, racks on the door, a shaft geared to the stationary racks and to the racks on the door, stationary guides forming bearings along which the shaft moves as the door is moved to open or closed position and guide means for guiding the door into horizontal position as the door is opened.
11. The combination with a structure having a door opening, of a door for closing the opening, said door being movable to vertical position to close the opening and being movable to horizontal, overhead, open position, means including racks on the door and structure and a floating shaft geared to the racks for guiding the door as it moves to either of said positions, a tensioning device arranged to counterbalance the door and whose tension is increased as the door moves to closed position and relieved as the door moves toward open position.
